UNITED STATES PATENT OFFICE.

JOSEPH CLAPP, OF EVANSTON, ASSIGNOR TO THE CLAPP AUTOMATIC FIRE EXTINGUISHER COMPANY, OF CHICAGO, ILLINOIS.

AUTOMATIC SPRINKLER.

SPECIFICATION forming part of Letters Patent No. 404,897, dated June 11, 1889.

Application filed September 4, 1888. Serial No. 284,520. (No model.)

To all whom it may concern:

Be it known that I, JOSEPH CLAPP, of Evanston, in the county of Cook and State of Illinois, have invented certain new and useful 5 Improvements in Automatic Sprinklers, of which the following is a full, clear, and exact description, reference being had to the accompanying drawings, forming a part of this specification, in which—

- 10 Figure 1 is a side view of said sprinkler in its normal condition. Fig. 2 is a side view of the same, partly in vertical section, the parts of the supporting-post being shown as they appear in the act of separation. Fig. 3 is a 15 perspective view of the supporting-post represented in Figs. 1 and 2. Fig. 4 is a view of the same taken at right angles to that shown in Fig. 1. Fig. 5 is a transverse sectional view of said post. Figs. 6, 7, 8, and 9 are 20 side views of modified forms of construction. Fig. 10 is a transverse sectional view upon the line $x x$, Fig. 7. Fig. 11 is a like view of a modification. Fig. 12 is a like view upon the line $y y$, Fig. 8. Fig. 13 is a like view upon the line $z z$, Fig. 9; and Fig. 14 is a transverse sectional view showing a modification 25 thereof.

Corresponding letters of reference in the different figures indicate like parts.

- 30 My invention relates to automatic sprinklers for fire-extinguishing purposes; and the object thereof is to provide a sprinkler which may be simple and cheap in its construction, extremely sensitive in its action, and yet one 35 which may be capable of withstanding a high air or water pressure and the shock incident to water-hammer.

To this end my invention consists in the construction and combination of elements 40 hereinafter more particularly described and claimed.

Referring to the drawings, a represents the usual discharge-pipe adapted to be connected in any well-known way with a distributing 45 system. The frame b of the sprinkler-head is preferably tapped upon the pipe in the manner shown, for purposes of adjustment, as hereinafter stated, and normally secured in any given position by means of a set-screw b' , 50 Fig. 1. A deflector c is arranged upon said frame before the discharge-opening, which is

normally closed by means of a cap d , held in position by means of a separable sectional post E , in which is primarily embodied the novelty of my invention. Said post may consist of two or more parts, and may be made wholly or partially of sheet metal, with numerous modifications or changes of form and appearance, without varying materially from the essential features of my invention, which 55 embodies, broadly, the following requirements—viz., that one of its members shall have a pivotal bearing upon the cap in the plane of its axis; that the body of said member shall extend upwardly in said plane and 60 laterally therefrom to near the frame; that one end of a secondary member shall bear against said frame and the other upon a point upon said primary member near to the cap and eccentric to the axis of the latter, and 65 that the contiguous surfaces of said members shall be united by means of fusible solder, so that they may have more or less of a sliding as distinguished from a breaking contact in 70 the act of separation at the ends which are 75 first to separate, or which tend to move in the arc of a circle, as hereinafter specified.

I will first describe the preferable form of construction of said post, after which I will refer to the modifications. I prefer to make 80 said post entirely of sheet metal, thereby enabling the parts to be formed in a die and to be strong in construction, while the thin plates which may be obtained in this way are more sensitive to changes of temperature than if 85 made of a larger bulk of metal.

Referring more particularly to Figs. 3, 4, and 5, $F F$ represent sheet-metal plates formed from brass, phosphor-bronze, or analogous material, preferably about three-quarters of the entire length of the post, which are crimped to form a flange f , in which the metal is doubled or bent upon itself, and flanges $f' f'$, which are in the same plane with each other and at right angles to that of the flange f . Two of said members $F F$ are placed with the flanges $f' f'$ parallel to each other, and between them are interposed, by preference, two members $G G$, formed from flat sheet-metal plates, which are of about the 90 same length as the parts $F F$, and the line of separation between which is in the plane of 95 100

- the flanges *ff*, as clearly shown in Fig. 5. Said members protrude from the lower ends of the members *F*, and are tapered, as shown at *g*, to a point in the plane of the flanges *f*.
- 5 The contiguous faces of said members are attached to each other by means of fusible solder *h*, Fig. 5. Projections *g' g'* upon said members *G* are formed at points eccentric to the axis of said post and serve as bearings, respectively, for the lower ends of the members *F F*. Said members may be tapered at the top or left of the full size, as desired.
- My improved sectional post is interposed between the cap *d* and the frame, so that the 15 points of the members *G* bear upon the axis of the cap. The pressure of the post upon the cap may be increased to any extent desired by turning the frame upon the screw-thread above described, and securing the 20 same in position by means of the set-screw *b'*. Upon the fusing of the soldered joints the members *G*, by reason of the eccentric bearing thereon, are thrown out in opposite directions, as shown in Fig. 2. It will be observed that when this action takes place the 25 separation is by a sliding contact of the members *F*, as distinguished from a direct and immediate separation. This feature affords greater resisting power to the post while in its normal condition, which is of vital importance in case of water-hammer or undue pressure. At the same time the joint is 30 equally sensitive to the action of heat and will separate just as readily when under proper conditions.
- In Fig. 6 I have shown a like construction to that in the former figures, except that but one member *G* is employed, and the bearing-points *g'* (but one of which is seen) are both 35 upon the same side of the axis.
- Figs. 7, 10, and 11 represent a single member *G* tapered to a point, but having the lateral extension of its body wholly upon one side of the plane of its axis, while the members *F* are made to correspond. In them the flanges *f* are of single thickness only.
- In Fig. 11 a slight modification of this feature is suggested in making but one member *F*, and bending it so as to inclose two sides 40 and the outer edge of the member *G*.
- In Figs. 8 and 12 I have shown each of the members *G* made in the form of a split cylinder and tapered to a knife-edge to bear in the plane of the axis of the cap, while the members *F* are bent to conform to the outer 45 surfaces thereof, to which they are soldered.
- Figs. 9 and 13 show the conditions reversed, the part *F* therein being a solid round post which is placed between the members *G*, 50 which are tapered to meet at a common point, and Fig. 14 shows the part *F* to consist of a hollow tube. It is obvious that these constructions are the same in principle as that first described. The members *G* in separating 55 have a sliding contact, but to a more limited extent than in the first-described construction, and one member has a positive

bearing upon the other eccentric to the plane of the axis of the post. I do not, therefore, confine myself to any specific form of construction except such as is limited to these features.

Having thus described my invention, I claim—

1. The combination, with the cap and frame 75 of an automatic sprinkler, of a separable intervening post having a member tapered to pivotally bear upon the axis of the cap, the body of which member is extended laterally from said axis, a secondary member having 80 one end resting against the frame and the other provided with a positive eccentric point of bearing upon said first member, the main body of one of said members being inclosed within the other and having their contiguous 85 surfaces united by means of fusible solder, whereby upon the yielding of the solder from heat said surfaces may slide laterally upon each other in the arc of a circle the center of which is said eccentric point of 90 bearing, substantially as shown and described.

2. In an automatic sprinkler, a sectional sheet-metal post for normally holding the cap in position, consisting of independent members of less length than the entire length of the post, the body of the members forming one section of said post having radial flanges extending from the axis thereof, one of said members being partially inclosed within the 100 other, fusible solder for uniting the contiguous surfaces of said members, and positive pivotal points of bearing therein eccentric to said axis, substantially as shown and described.

3. The combination, with the cap and frame 105 of an automatic fire-extinguisher, of a sectional cap-holding post consisting of two independent sheet-metal members tapered to a point at and having a bearing upon the axis 110 of the cap, one or more members soldered thereto to form the remainder of the post, which rests against the frame, and bearings or rests upon said tapered members eccentric to the axis thereof, substantially as shown 115 and described.

4. In an automatic sprinkler, a sectional sheet-metal post for normally holding the cap in position, consisting of two independent members of less length than the entire length 120 of the post, pointed to meet and bear in common upon the axis of the cap, the bodies of which members extend laterally from said axis, one or more secondary members attached thereto with fusible solder and having 125 eccentric points of bearing thereon, substantially as shown and described.

In testimony whereof I have signed this specification, in the presence of two subscribing witnesses, this 23d day of August, 1888.

JOSEPH CLAPP.
